UNITED STATES PATENT OFFICE.

EDWARD C. BREKKEN, OF PEKIN, NORTH DAKOTA.

DUPLEX REGISTER.

Application filed August 27, 1925. Serial No. 52,779.

This invention relates to registers or ventilators located between a lower room and an upstairs room, and more specifically relates to duplex registers in which air passes both upward and downward therethrough.

The object of my present invention is to provide a device which will permit two currents of air to pass therethrough from opposite directions and at the same time, without the currents interfering with one another. A further object is to provide such a device which will be simple, efficient and inexpensive in both construction and operation.

Referring to the drawings which constitute a part of this application:

Fig. 1 is a longitudinal section through one embodiment of my invention.

Fig. 2 is a top plan view thereof with a portion broken away.

Fig. 3 is a longitudinal section through a modification.

Fig. 4 is a top plan view of such modification.

Fig. 5 is a section on the line 5—5 of Fig. 3.

Fig. 6 is a sectional view of a further modification.

In the embodiment of my invention shown in Figs. 1 and 2, A represents the ceiling of a room and B represents the floor of a second room directly above, between which rooms a circulation of air is desired. Cut through both the ceiling A and floor B is an opening to receive my improved duplex register, which includes register plate C, outer pipe D, partition E, inner pipe F and damper G.

The register plate C covers the floor opening and is secured to the floor by screws C¹, or by any other suitable fastening means. The register plate C is provided with a downwardly projecting flange C² of a size and shape to fit within the floor opening, and grating openings C³ permit air to pass up and down through the register plate C.

The outer pipe D is of such shape and dimensions as to fit within the opening in ceiling A and floor B, and is formed with a flange D¹ to aid in properly positioning the pipe within the opening. The pipe D is provided with an extension D² to permit adjustment to adapt it for use with different sizes of floor joists between floors. This extension D² is secured to the register plate C and telescopes into the upper end of the

main outer pipe D. Between pipe D and extension D² a pin and inclined slot connection D³ is shown to permit proper adjustment.

Within the pipe D and approximately midway of its length, a partition E is secured by means of a flange E¹. The partition E is solid except for a central opening in which is fitted and secured an inner pipe F.

This inner pipe F, like the outer pipe D, is shown of cylindrical form, but may be of square, oblong, hexagonal or any other cross-sectional shape. Preferably, the pipe F is tapered inwardly at the bottom and extends slightly below the level of the ceiling, as shown at F¹. The pipe F is provided with an extension F², which telescopes over the upper end of pipe F, and is adjustably connected thereto by a pin and inclined slot connection F³. The extension F² is fixed to and projects slightly above the register plate C, and has its upper end inwardly tapered, as shown at F⁴.

The walls of the pipe F are solid and continuous except for two openings F⁵ and F⁶ which are cut in opposite sides in the pipe F. The opening F⁵ is formed by cutting away the wall of the inner pipe F from a point F⁶ slightly above the lower end of the inner pipe up to a point F⁷ at the partition E. Similarly, the opening F⁶ is formed by cutting away the wall of the inner pipe F from a point F⁸ slightly below the upper end of the inner pipe down to point F⁹ at partition E.

Within the inner pipe F, a damper G is pivoted on a pin G¹ which projects horizontally across the inner pipe F and which has its ends secured to diametrically opposite sides of the inner pipe. The damper G is pivoted near its center and is made of such contour as to conform to the shape of the inner walls of the pipe F, when extending diagonally, as shown in Fig. 1, from about point F⁶ to about point F⁹. Thus in the case of the cylindrical pipe F, shown in Figs. 1 and 2, the damper G is of somewhat oval shape.

In operation, it is obvious that the warm air in the room below will rise to the ceiling A and will follow along the ceiling until it comes to the register opening, where it will go in, seeking an outlet up. The partition E prevents the warm air from passing directly upwards between pipes D and F.

With the damper in the position shown in Fig. 1, the warm air enters through opening F^3 into pipe F and passes up through pipe F , as shown by arrows, to the room 5 above.

At the same time the cool air in the room above will fall to the floor B and will follow along the floor B until it comes to the register opening, where it will go in, seeking an outlet down. The partition E prevents this cool air from passing directly downward between pipes D and F . With the damper in the position shown in Fig. 10 1, the cool air enters through opening F^8 into pipe F and passes down through pipe F , as shown by arrows, to the room below.

Thus, it is clear that the cool air from the room above can go down into the room below and the warm air from the room below can go up into the room above, without interfering in any way with each other and thus insuring perfect circulation between the two rooms. The inner pipe F and extension F^2 have their outer ends inwardly tapered and extending slightly below the ceiling and slightly above the floor, in order to prevent the cool air from above and the warm air from below entering directly into the inner pipe F . If no circulation is desired, the damper may be tilted over the other way and thus close the register, preventing air from passing either up or down through the register.

In Figs. 3, 4 and 5, I have shown a modification showing a slightly different embodiment of my invention. In this form the construction and operation are, in general, similar to the form shown in Figs. 1 and 2. There are these differences, however, that in 35 the modification a. plurality of cool air chutes and a plurality of warm air chutes are provided, instead of the single cool air chute and the single warm air chute of Figs. 1 and 2, and further, it will be noted that 40 the damper G of the preferred form has been omitted in this modification.

Thus, in Figs. 3, 4 and 5, I have designated the ceiling and floor as H and I , respectively, while the register plate J is 45 fastened to the floor by screws J^1 , and grating openings J^2 are provided to permit the air to pass through. Also, the outer pipe K is provided with an annular flange K^1 and fits within the opening in ceiling H . An extension K^2 , fixed to register plate J , 55 telescopes into the upper end of pipe K and is adjustable by pin and inclined slot connection K^3 .

Within outer pipe K and approximately 60 midway of its length, a partition L is secured, having a central opening in which is fitted and secured an inner pipe M , tapered inwardly at its bottom as at M^3 and extending slightly below the level of the ceiling. An extension M^2 , fixed to register plate J

telescopes over the upper end of inner pipe M and is adjustably connected thereto by a connection similar to K^3 .

As described thus far, the modification is similar to the preferred form, but the modification differs from the preferred form in the number of air openings, in the provision of individual air chutes and in the omission of a damper. Thus, instead of the single warm air opening F^3 of Fig. 1, I provide in Figs. 3, 4 and 5, three warm air openings N , equally spaced from each other in the cylindrical wall of pipe M and located between the partition L and the lowered tapered end M^3 of inner pipe M . Also, instead of the single cool air opening F^8 of Fig. 1, I provide in Figs. 3, 4 and 5, three cool air openings O , equally spaced from each other in the cylindrical wall of pipe M , and located between the partition L and the upper end of inner pipe M . Just as in Fig. 1, the cool air opening F^8 above the partition is opposite the warm air opening F^3 below the partition, likewise in Figs. 3, 4 and 5, the cool air openings O are respectively opposite the three warm air openings N below the partition.

In order that warm air entering openings N shall be directed upwardly through inner pipe M , I provide warm air chutes N^1 , and similarly in order that cool air entering openings O shall be directed downwardly through inner pipe M , I provide cool air chutes O^1 . The inlet mouths of the warm air chutes N^1 register with the respective warm air openings N , and the inlet mouths of the cool air chutes O^1 register with the respective cool air opening O .

The outlet mouths of the warm air chutes N^1 are preferably of V-shape and open upwardly within the inner pipe M , whereas the outlet mouths of the cool air chutes O^1 are also preferably of V-shape, but open downwardly within inner pipe M . By reason of being located opposite, as above described, the openings N and, hence the registering covered chutes N^1 are in alternate or staggered relation respectively to the openings O and registering covered chutes O^1 , so that there is no possibility of the cool air currents issuing from the cool air chutes interfering with the warm air currents issuing from the warm air chutes.

In this modified form of Figs. 3, 4 and 5, there is no damper to cut off the circulation of the air, but in other respects the operation is the same as in the form shown in Fig. 1, the warm air from the room below entering the openings N to be directed by chutes N^1 upwardly through pipe M to the room above, and the cool air from the room above entering the openings O to be directed by chutes O^1 downwardly through pipe M to the room below.

In Fig. 6 I have shown how the con-

struction of Figs. 3, 4 and 5 would be modified if the outer pipe were of the polygonal cross-section Q and if the inner pipe were also of the polygonal cross-section R, instead of the cylindrical forms of the other figures. In this form the letters S¹ and T¹ represent respectively the upwardly directed warm air chutes and the downwardly directed cool air chutes. In spite of this 10 change of shape, the function and operation of this form is the same as for the above-described modification.

While in accordance with the provisions of the statutes, I have illustrated and described the best embodiments of my invention now known to me, it will be apparent to those skilled in the art that changes may be made in the subject matter and form of the invention disclosed without departing 20 from the spirit of my invention as set forth in the appended claims, and that in some cases certain features of my invention may be used to advantage without a corresponding use of other features.

25 I claim:

1. In a device of the class described, spaced outer and inner pipes, a partition between said pipes, said inner pipe being provided with an opening on each side of 30 said partition, and means for conducting air currents respectively entering said openings in opposite directions through said inner pipe.

2. In a device of the class described, 35 spaced outer and inner pipes, a partition between said pipes, said inner pipe being provided with an opening on each side of said partition, and means mounted within said inner pipe, for conducting air currents 40 respectively entering said openings in opposite directions through said inner pipe.

3. In a device of the class described, 45 spaced outer and inner pipes, a partition between said pipes, said inner pipe being provided with an opening on each side of 50 said partition, and a damper pivoted within said inner pipe for either conducting air entering said openings in opposite directions through said inner pipe or for preventing air passing through said inner pipe.

4. In a device of the class described, 55 an outer tubular member, an inner tubular member mounted within and spaced from said outer tubular member, and means for conducting an air current in one direction 60 through a portion of each of said tubular members and for simultaneously conducting another air current in the opposite direction through a portion of each of said tubular members.

5. In a device of the class described, 65 an outer tubular member, an inner tubular member mounted within and spaced from said outer tubular member, and means for conducting air entering one end of said outer

tubular member and passing into said inner member and out through one end of said inner tubular member and for simultaneously conducting air entering the other end of said outer tubular member and passing 70 into said inner member and out through the other end of said inner tubular member.

6. In a device of the class described, an outer tubular member, an inner tubular member mounted within and spaced from 75 said outer tubular member, a partition between said tubular members, the wall of said inner tubular member being provided with an opening on each side of said partition, and means for conducting air entering one 80 of said openings in one direction inside said inner tubular member, and for simultaneously conducting air entering another of said openings in the opposite direction inside said inner tubular member. 85

7. In a device of the class described, an outer tubular member, an inner tubular member mounted within and spaced from said outer tubular member, a partition between said tubular members, the wall of 90 said inner tubular member being provided with an opening on each side of said partition, and means mounted within said inner tubular member for conducting air entering one opening in one direction inside said 95 inner tubular member, and for simultaneously conducting air entering the other opening in the opposite direction inside said inner tubular member.

8. In a device of the class described, an outer tubular member, an inner tubular member mounted within and spaced from 100 said outer tubular member, a partition between said tubular members, the wall of said inner tubular member being provided with 105 an opening on each side of said partition, and a damper pivoted within said inner tubular member and adapted when in one position to permit and in another position to prevent air entering the lower opening to 110 pass through the upper end of the inner tubular member and air entering the upper opening to pass through the lower end of the inner tubular member.

9. In a device of the class described, an outer tubular member, an inner tubular member mounted within and spaced from 115 said outer tubular member, the ends of said inner tubular member being inwardly tapered and extending beyond the adjacent 120 ends of the outer tubular member, a partition between said tubular members, the wall of said inner tubular member being provided with an opening on each side of said partition, and a damper member within and 125 extending across said inner tubular member, each opening being between said partition and said damper.

10. In a duplex register adapted to be positioned in an opening between upper and 130

lower rooms, a register plate adapted to be secured to the floor of the upper room to overlie said opening, an outer pipe adapted to fit within said opening and to extend 5 from the ceiling of the room below to the floor of the room above, a partition extending transversely across said outer pipe, and provided with a central opening therein, an inner pipe located within said central 10 opening, a damper extending obliquely across said inner pipe and pivoted therein, the wall of said inner pipe intermediate its ends being provided with an upper opening above said partition and below said damper, 15 and with a lower opening below said partition and above said damper, whereby cold air from the upper room descending into the space above the partition between the outer and inner pipes enters through said upper

opening into said inner pipe and passes out 20 through the lower end of said inner pipe into said lower room, and simultaneously warm air from the lower room ascending into the space below the partition between the inner and outer pipes enters through 25 said lower opening into said inner pipe and passes upwardly and out through the upper end of said inner pipe into said upper room, said inner pipe having its ends tapered inwardly and having its ends extending above 30 said floor and below said ceiling, respectively, thereby preventing cold air from the room above entering directly into the upper end of the inner pipe, and preventing warm air from the room below entering directly 35 into the lower end of the inner pipe.

EDWARD C. BREKKEN.
